The ornamental design for an emotional indicator device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of an emotional indicator device showing my new design;

FIG. 2 is a top elevational view of the thereof;

FIG. 3 is a bottom elevational view thereof;

FIG. 4 is a left side elevational view and a mirror image of a right side elevational view thereof; and,

FIG. 5 is a rear elevational view thereof.

The transparent strips with arrows labeled "F" and "I" thereon are independently rotatable about the center of the dashed line circle near the bottom of the device. The broken lines are included for the purpose of illustrating portions of the emotional indicator device that form no part of the claimed design.
